UNITED STATES PATENT OFFICE

ARTHUR LANE, OF MIDDLETOWN, OHIO

ELECTRIC SIGNALING APPARATUS

Application filed November 11, 1926. Serial No. 147,776.

The present invention relates to improvements in electrical signaling systems and has particular reference to an improved control apparatus therefor.

5 An important object of the invention is to provide an apparatus designed for intermittently operating a plurality of fire signals.

10 A further object of the invention is the provision of an apparatus which will automatically operate for a predetermined period of time.

15 A still further object of the invention is the provision of an apparatus of the above character which is positive in operation and which will be reliable in use.

20 Still another object of the invention is the provision of a signaling apparatus of the above type which is comparatively simple yet durable in construction and which can be manufactured at a relatively low cost.

25 Other objects and advantages of the invention will become apparent as the description progresses.

In the accompanying drawings forming a part of this application and in which like reference characters are employed to designate corresponding parts throughout the same:

30 Figure 1 is a front elevational view of my improved apparatus,

Figure 2 is a side elevational view of the same;

Figure 3 is a top plan view of the apparatus;

35 Figure 4 is a bottom plan view,

Figure 5 is a vertical transverse sectional view taken through the center of the structure,

40 Figure 6 is a horizontal transverse sectional view taken on the horizontal center line,

Figure 7 is an enlarged detail view of the intermittently operable gear wheel, and

45 Figure 8 is a horizontal sectional view through the adjustable governor controlling mechanism.

The present apparatus is designed primarily for the purpose of operating fire alarm signals at the intersection of congested thoroughfares to warn crossing traffic of the approach of the fire apparatus.

Signals of this character are usually sounded for a predetermined period of time, sufficient to warn traffic, at the intersection, of the approach of fire apparatus so that the intersection may 55 be cleared to avoid the possibility of collision or cause the delay of the fire apparatus. The signaling mechanism is connected in a rather extensive system and the present apparatus is designed to control the operation of a series of signals for a suitable period of time 60 while opening the circuit to disconnect various other signals.

Referring more particularly to the structure embodying my invention, the numeral 65 10 generally designates a casing embodying a front casing plate 11 and a rear casing plate 12. These plates are held in spaced vertical positions by means of transverse spacing posts 13. A transverse base 14 is supported 70 between the upper portions of the plates, this base being of insulating material and provided at its forward central portion with a rectangular recess. Rigidly secured to the rear portion of the base 14 and extending vertically upward therefrom is a contact support 15, held in upright position by machine screws 16. This support is constructed of fiber or other insulating material and is provided with a longitudinal recess 17 in its lower portion, the purpose of which will become 75 apparent as the description progresses.

Journalized in the central portions of the front and back plates 11 and 12 is a rotatable main shaft 18, the forward end thereof having a non-circular extension 19 for the application of a winding key. Rigidly secured adjacent the forward end of the shaft 18 is the hub of a ratchet wheel 20. Rotatably fitted on the outer end of the said hub is 80 a comparatively large gear 21. Secured on the inner end of the hub 20 is a circular guide plate 22, a ring 23 being rigidly secured between the gear 21 and guide plate adjacent their peripheral edges. A notch 24 is formed 85 in the periphery of the ring 23, for a purpose which will later appear.

Secured at one end to the main shaft 18 and wound thereon is an actuating spring 25, the outer end of which is secured to one 90 100

of the spacing posts 13, as shown to advantage in Figure 1. This spring is held in position by the guide plate 22 and a complementary guide plate 26 arranged at the other side of the spring.

5 The gear 21 is in mesh with a gear train comprising gears 27 and pinions 28 secured to the gears 27 and rotatable upon a series of transverse shafts 29. This gear train provides a speed increasing mechanism adapted to drive a governor or speed regulating device mounted in the lower portion of the apparatus. This governor is mounted upon a shaft 30 and comprises a pair of spaced collars 31 mounted on the governor shaft 30, one of the collars having a pinion 31' secured thereto in mesh with one of the gears 27 of the gear train. Secured at their ends to the collars 31 and extending horizontally therebetween are a plurality of resilient governor arms 32. Secured to the central portions of the governor arms are weights 33. As the governor is operated at a comparatively high speed, the forward collar 31 is slidably actuated upon the governor shaft by the outward flexing of the arms 32, a circular brake disk 33' being secured to the said governor collar and rotatable therewith.

As it is desired to control the speed of rotation of the ring 23 and gear 21, an adjustable regulating mechanism is provided comprising a resilient arm 34 having its outer free end offset from the front plate 11 and disposed at an angular position and its inner end rigidly secured to the said front plate.

Disposed against the inner end of the arm 34 is a plate 35 formed with a longitudinal slot 36 through which and the plate 12 securing bolts 37 are fitted. The offset end of the arm 34 carries a head 38 having secured to its inner side a brake shoe 39 formed of leather or other suitable material. As can be readily noted from the drawing, the head 38 and brake shoe 39 are disposed opposite the face of the brake disk 32 and during the rotary motion of the governor, the disk is moved towards the shoe 39 and frictionally contacts therewith to reduce the speed. The tension of the arm 34 is adjusted by means of a screw 40 threaded in a sleeve 41 formed on the front casing plate and projecting outwardly. The outer end of the screw 40 carries an actuating knob 41' carrying a pointed indicating arm 42. Thus, by rotary movement of the knob 41', the screw 40 may be inwardly adjusted, in contact with the arm 34, to urge the arm inwardly and thereby permit increase in the speed of operation of the mechanism or reversely adjusted to permit the arm to move inwardly by its resiliency and thereby reduce the speed of operation of the mechanism.

Referring particularly to Figure 1 of the drawings, it will be noted that the gear 21 is rotatably driven through the instrumen-

tality of a pivoted pawl 43 carried by the ring 23 and having its forward tapered extremity normally in engagement with the ratchet 20. This pawl is held in engaging position by means of a spring 44 embedded in the annular ring and contacting with the pawl. Thus, rotary movement of the central shaft 18 and ratchet 20 carried thereby will rotatably actuate the gear 21 and gear train in mesh therewith, causing simultaneous rotary movement of the governor shaft.

The apparatus is designed to operate continuously during one revolution of the gear 21, this limited movement of the gear being controlled by a fulcrumed tripping lever having a bearing collar 45 pivoted on the intermediate portion of one of the spacing posts 13 and formed with a laterally projecting tapered trigger arm 46. The inner end of the tripping lever is formed with an arcuate upwardly projecting trip arm 47, curved to conform to the periphery of the ring. Pivoted to the upper end of the trip arm 47 is a lug 48 extending downwardly from the trip arm and adapted to engage in a recess 24 formed in the ring 22. This lug is held in the position shown in Figure 7, by its engagement against the periphery of the ring 23 while the ring 23 is rotating, but moved to position to engage in the recess 24 by a tension spring 49 secured to the lug and held in a pocket in the trip arm 47. From this description, it will be noted that swinging movement of the tripping lever will disengage the lug 48 from the recess 24 and permit one complete revolution of the ring 23 and gear 21 and operation of the gear train and governor during the period of time the gear 21 is rotating.

Slidably mounted in the recess formed in the base 14 and adapted for vertical reciprocating movement therein is a rectangular plunger 50 preferably formed of insulating material and carrying a horizontally extending contact bar 51 on its upper end. This bar is secured to the plunger 50 and the plunger is normally urged downwardly by a bowed spring 52 of substantially semi-elliptic form, the intermediate portion of the spring being secured to the lower end of the plunger and the ends of the spring being curved upwardly and in contact with the lower surface of the base. It will be noted that the lower end of the plunger 50 rests upon the upper end of the trip arm 47 so as to be vertically reciprocated when the trip arm is oscillated.

Securely mounted on the upper edge of the contact support 15 are a plurality of resilient contact fingers 53 and 54, the fingers 53 being arranged on the intermediate portion of the support and projecting forwardly in an elevated position while the contact fingers 54 are arranged on the end portions of the support and offset to extend, at their ends, in a lower horizontal plane. Secured to the lower

5 sides of the upper contact fingers 53 and the upper sides of the lower fingers 54 are contact points 55. The contact points carried by the fingers 53 and 54 are arranged in vertical alignment with points 56 secured on the upper and lower sides of the bar 51 respectively for intermittent contact.

10 Thus, the contact points engageable with the fingers 53 are disposed on the upper side of the contact bar while the points engageable with the fingers 54 are arranged on the under side of the bar. From this construction, it is obvious that when the contact bar is in its normal lowered position, the fingers 15 54 will be in contacting position and the circuit through the contacts 55 and 56, carried by these fingers and the bar 51, will be closed. When the contact bar 51 is elevated the circuit through the fingers 53 will be closed to 20 operate suitable signal mechanisms. Suitable binding posts 57 are mounted on the contact fingers 53 and 54 to permit convenient connection of electric circuit wires while the circuit is completed by the connection of 25 wires with the contact bar 51.

30 In operation, my improved control apparatus provides for periodic operation of apparatus connected in circuit therewith. The primary purpose of my improved structure is to provide a simplified control apparatus by means of which a plurality of alarm signals may be operated for a predetermined period of time, at the expiration of which the signal circuits will be opened and the 35 control apparatus automatically rendered inactive. The apparatus is set in operation by depressing the trigger arm 46 thereby rocking the tripping lever and causing the lug 48 to disengage from the recess 24. When this 40 occurs, the spring 25 which is maintained in a tightly wound condition, will actuate the ratchet wheel 20, gear 21 and ring 23 for a complete cycle of rotary movement. During this movement of the gear 21, the gear 45 train will also be operated and the governor mechanism simultaneously operated. As previously indicated, the speed of the gear mechanism may be regulated by adjustment of the screw 40 which regulates the speed of 50 the governor and thereby determines the period of time necessary for one complete cycle of operation of the mechanism. The angular position of the arm 34 may be readily adjusted by slidably adjusting the plate 35 with 55 respect to the inner end of the arm.

59 After the completion of one revolution of the gear 21, the lug 48 will again engage the recess 24 and the apparatus will be locked in its initial starting condition.

60 From the construction of the apparatus, it will be readily apparent that, as the tripping lever is rocked about its pivot, the plunger 50 is vertically elevated against the tension of the spring 52. In the uppermost position 65 of the bar 51, while the lug 48 rides on the

periphery of the ring 23, the intermediate contact points on the contact bar 51 and contact fingers 53 will mutually engage and thus close a series of alarm circuits. As soon as the operating cycle is completed and the 70 mechanism is restored to its normal inactive condition, the contacts 54 will be in engagement with the corresponding contact points on the bar 51 to close the circuit to a normally set safety signal. From the foregoing 75 description and the drawings, it will be readily seen that a compact and durable signal circuit control mechanism has been devised whereby a plurality of fire alarm signals may be maintained in operative position for a predetermined period of time. The construction is such as to provide an apparatus which will be very accurate in performance and which will require very little attention. It is of course, necessary that the spring 25 80 be maintained in a tightly wound condition and that the trigger arm 46 be actuated to start the operation of the mechanism. After the tripping operation, the apparatus will automatically close certain contact circuits 85 for a suitable period of time and at the expiration of this time open the circuits and restore the mechanism to its starting condition.

90 It is to be understood that the form of my invention herewith shown and described is to be taken as the preferred example of the same and that various changes as to the shape, size and arrangement of parts may be resorted to without departing from the spirit of the invention or the scope of the subjoined 95 claims.

Having thus described my invention, what is claimed is:

1. Control mechanism for electric signaling circuits comprising a contact member, sets of spaced contacts arranged at opposite sides of said contact member and in spaced relation thereto, a member supporting the contact member for reciprocating movement between said sets of contacts to position bridging the contacts of either set, a rotary member, motor means for rotating the same, a detent arranged, in one position of adjustment, to restrain the rotary member from rotation, and means yieldably urging the detent 105 to such position and the supporting member to one of its positions of movement, the said detent being manually adjustable to another position coacting with the said rotary member and the supporting member to hold the 110 latter in its other position of movement.

2. Control mechanism for electric signaling circuits comprising a contact member, sets of spaced contacts arranged at opposite sides of the said contact member and in spaced relation thereto, a member supporting the contact member for reciprocating movement between said sets of contacts to position bridging the contacts of either set, a rotary member having a recess in its periphery, 125

motor means for rotating the said rotary member, a detent comprising a manually operable rocking lever, a lug upon the rocking lever for engagement in the recess in the said 5 rotary member, in one position of adjustment of the rocking lever, whereby to restrain the rotary member from rotation, and means yieldably urging the said supporting member to one position of its movement and coact- 10 ing with the said lever to hold the same in position with the lug in engagement in the said recess, the lever being manually adjustable to effect retraction of the lug from the recess and the engagement of the lug with the per- 15 phery of the rotary member and movement of the supporting member to effect movement of the contact member to its other position of movement and whereby the said supporting member will be held in said position until the said lug is reengaged in the recess. 20

3. Control mechanism for electric signaling circuits comprising a contact member, sets of spaced contacts arranged at opposite sides of said contact member, a base having 25 an opening therein, a supporting member mounted for reciprocating adjustment in said opening and supporting said contact member for movement between the sets of contacts, a bowed leaf spring secured at its intermediate portion to the said supporting member and engaging at its end portions against the said base and yieldably urging the said supporting member in a direction to hold the contact member in one of its positions of 30 movement and in position bridging one of the sets of contacts, a rotary member, motor means for rotating said member, means for controlling the speed of rotation of said member, the member having a recess in its per- 35 phery, a detent comprising a pivoted lever having one end in engagement between the said supporting member and the said rotary member, and a lug pivoted to the said arm of the lever and, in one position of rotation of 40 the rotary member engaging in said recess, the said lever being adjustable to retract the lug from engagement in the recess and effect adjustment of the supporting member to move the contact member to the position 45 bridging the contacts of the other set and with the said lug in engagement with the periphery of the said rotary member during a complete revolution of said member. 50

4. Control mechanism for electric signaling circuits comprising a contact member, sets of spaced contacts arranged at opposite sides of said contact member and in spaced relation thereto, a member supporting the said contact member for reciprocating move- 55 ment between the said sets of contacts to position bridging the contacts of either set, means yieldably urging the supporting member to one position of its movement, a rotary mem- 60 ber, motor means for rotating the said rotary member, and a detent coacting with said ro-

tary member to hold the same against rotation, in one position of rotary movement of said member, and yieldably held in coactive relation thereto by the urging means of the supporting member, the said detent being 70 manually movable to inactive position to release the rotary member for rotary movement and to move the supporting member to its other position of movement. 75

In testimony whereof I affix my signature. 75
